UNITED STATES PATENT OFFICE.

WILLIAM H. COOPER, OF NEW HAVEN, CONNECTICUT, ASSIGNOR TO M. SEWARD & SON, OF SAME PLACE.

CARRIAGE-CLIP.

SPECIFICATION forming part of Letters Patent No. 283,976, dated August 28, 1883.

Application filed June 18, 1883. (No model.)

To all whom it may concern:

Be it known that I, WM. H. COOPER, of New Haven, in the county of New Haven and State of Connecticut, have invented new Improvements in Carriage-Clips; and I do hereby declare the following, when taken in connection with accompanying drawings and the letters of reference marked thereon, to be a full, clear, and exact description of the same, and which said drawings constitute part of this specification, and represent, in—

Figure 1, a side view; Fig. 2, a top view; Fig. 3, a transverse section.

This invention relates to an improvement in clips for carriages, with special reference to clipping the springs to the cross-bars. Unlike the clips which embrace the bar in the clipping of other springs and parts to a carriage, the legs of this clip pass down through holes in the bar in a plane parallel with the bar itself; hence to make a neat job it is desirable that the body of the clip shall lie flush with the surface of the bar. They are therefore let into the bar by cutting a groove corresponding to the shape of the body of the clip. In the usual construction these clips have been made **U** shape, with the body flat on its under side and rounded upon the back; hence a square recess must be cut in the bar. This square or angular shape makes it difficult to cut a groove into which the body will perfectly fit.

The object of my invention is to construct the clip with a body of a shape which will permit an easy fitting of the body into the bar; and it consists in the construction of the clip, as hereinafter described, and more particularly recited in the claims.

A represents the body; B B, the two legs, which are formed at right angles to the body, and distant from each other according to the

width of the spring. In transverse section this body is flat upon its upper surface, as seen in Fig. 3, and curved or semi-polygonal upon its under surface, so as to come to substantially a sharp edge at the two sides, and in width greater than the diameter of the legs. At the two ends the body preferably projects, as at a, and in circular shape concentric with the legs, as seen in Fig. 2, the under surface curved. To fit this body to the bar it is only necessary to bore the holes for the two legs—that is, countersink the two holes upon the surface of the bar corresponding to the two ends a a of the body. Then with a gouge cut across from one countersink to the other. This, therefore, not only facilitates the cutting or fitting of the body, but insures a more accurate fit. The two ends a a need not project beyond the line of the legs; but I prefer to do this, as it renders the countersinking more easily performed; but if standing flush with the sides of the legs the gouge employed readily cuts the proper curve for the ends, and across from end to end to receive the body.

I claim—

1. The herein-described carriage-clip, consisting of the body A, two legs, B B, said body flat upon its upper surface and in transverse section curved or semi-polygonal shaped upon the under side, substantially as and for the purpose described.

2. A carriage-clip consisting of the two legs B, the body A, flat upon its upper surface, curved upon its under side in transverse section, its ends projecting in a circle concentric with the legs, substantially as described.

WM. H. COOPER.
